(57) **CLAIM**

The ornamental design for a display screen with shipment management graphical user interface, as shown and described.

DESCRIPTION

FIG. 1 is a front view of a display screen with shipment management graphical user interface showing my new design;

FIG. 2 is a front view of a second embodiment thereof; FIG. 3 is a front view of a third embodiment thereof; and, FIG. 4 is a front view of a fourth embodiment thereof. The outermost broken line illustrates a display screen and the remaining broken lines illustrate portions of the shipment management graphical user interface. None of the broken lines form part of the claimed design.

1 Claim, 4 Drawing Sheets
